UNITED STATES PATENT OFFICE.

NICHOLAS J. CONRAD, OF CHICAGO, ILLINOIS, ASSIGNOR TO SCHWEITZER & CONRAD, A CORPORATION OF ILLINOIS.

FUSE OR LIKE DEVICE.

1,215,491.

Specification of Letters Patent. Patented Feb. 13, 1917.

Application filed April 19, 1913. Serial No. 762,249.

To all whom it may concern:

Be it known that I, NICHOLAS J. CONRAD, a citizen of the United States, residing at Chicago, in the county of Cook and State 5 of Illinois, have invented a certain new and useful Improvement in Fuse or like Devices, of which the following is a full, clear, concise, and exact description, reference being had to the accompanying drawings, 10 forming a part of this specification.

My invention relates to an improvement in fuse or like devices. The principal object of my invention is to provide a fuse or like device which shall present no live parts 15 which may be touched by an operator, and in which all the metallic parts are inclosed by insulating material.

A further object of my invention is to provide a fuse or like device having a holder 20 or clip which is normally closed, but which may open to relieve interior pressure.

A further object of my invention resides in the particular arrangement and combination of parts hereinafter described.

25 In the accompanying drawings Figure 1 is a longitudinal sectional view of my improved fuse or like device. This view shows a fuse cut-out held by holders or clips in operating position, the upper part of the 30 cut-out being shown in full lines and the lower part in dotted lines. The inclined dotted lines in this figure show the position of the cut-out when being inserted into the clips or holders, or removed therefrom.

35 Fig. 2 is a plan view of the lower holder or clip shown in Fig. 1, the cut-out being removed.

In the different views the same parts are referred to by the same reference numerals.

40 Referring more particularly to the drawings, 1 is a slab of marble, slate or similar material, upon which a cut-out device is to be mounted, as for instance when used with a potential transformer. 2—2 are porcelain 45 insulators of any convenient style. The insulators 2—2 inclose copper connecting rods or pieces 3—3, which project beyond the outer ends of the insulators and are shown in section in Fig. 1. 4—4 are insulating 50 cover pieces of fiber or other suitable material, which are made to fit the surface of the parts 3—3 exterior to the insulators 2. As indicated in Fig. 2, the conducting rods 3 and covers 4 are grooved in a vertical di- rection so as to receive cylindrical or tubular 55 clip members 5—5, which are attached to the outer faces of the rods 3—3 by means of the screws 6—6, so that parts 3 and 5 are held in good electrical connection. Surrounding the metallic cylinders 5—5, previously referred to as clip pieces, are fiber cylinders 7—7 which completely inclose the clip pieces except at the point where the cylinders are cut away to afford contact between the clip pieces 5 and the rods 3. The lower end of 60 the lower cylinder or clip piece 5 is closed by a metallic disk 8, while immediately below the disk 8 is a fiber disk 9 which screws into the lower end of the cylinder 7 as shown in Fig. 1, and serves to retain the plate or 65 disk 8 in place. On the other hand the upper end of the upper fiber cylinder 7 is closed by a fiber disk or plate 10 which is shown as hinged to the upper cylinder 7. Plate 10 is thus lightly held in position and 70 may fly back to open the interior of the upper cylinder to the atmosphere in case any pressure is generated within the upper cylinder upon the operation of the fuse. It is 75 obvious, however, that various ways might 80 be employed for normally holding the plate 10 in place while allowing it to open the cylinder upon the application of internal pressure. Within the cylindrical clip members 5—5 are mounted a number of metallic 85 spring holding or contact members 11—11 projecting inwardly. The spring members 11 are attached to the upper member 5 at its lower edge and to the lower member 5 at its upper edge, and run parallel to the 90 axes of the members 5, the upper ends of the upper members 11 and the lower ends of the lower members 11 being free to move to allow the springs to accommodate themselves to the position of the cut-out when it is inserted in the clips. The cut-out device 95 shown is indicated by the numeral 12. The cut-out 12 may be of any standard design having metallic cap or contact pieces 13—13, which contact with the spring members 11. 100 This style of mounting is however particularly well adapted for use in connection with fuses of the type shown in patents to Schweitzer and Conrad No. 1,135,548 and others which type is characterized by vent- 105 ing of the pressure caused by violent blowing of a fusible member axially of the fuse or cutout. The lower cap piece 13 rests upon

the metallic plate 8 when the device is in operative position. As indicated by dotted lines in Fig. 1, the operation of inserting or withdrawing a fuse from my improved form 5 of clip is markedly different from that employed with the present standard form of clips.

My cylindrical clip members 5 being in longitudinal alinement the axis of the cut-out must be inclined to that of the clip members 10 in order that it be inserted or withdrawn, the upper clip 5 and its fiber protector 7 being sufficiently long so that the cut-out may be inserted therein sufficient 15 distance to clear the upper edge of fiber cylinder 7, while in the inclined position. The cut-out can then be swung into alinement with the lower clip member and pushed into it, whereupon the spring members 11 20 will hold the cut-out in an operating position.

It will be obvious to those skilled in the art that changes and modifications may be made in my device without departing from 25 the spirit of my invention.

It is particularly evident that while I have shown my improved clips in a vertical position that they may be used in a horizontal or inclined position when desired.

Having thus described my invention, what I claim is:

1. The combination of a supporting member, a pair of insulators mounted on said supporting member, metallic rods extending 35 through said insulators, a pair of separate insulating housings axially in line with each other, said housings being permanently secured to the ends of said rods opposite said supporting member, said housings containing metallic contact devices for a fuse 40 device, said contact devices having spring means for yieldingly holding the fuse device.

2. The combination of a pair of holders 45 made with sockets to receive the end of a fuse, one of said sockets being closed at its end farthest from the other socket, and said other socket having its end farthest from the first mentioned socket provided with an 50 openable end piece.

3. In combination an insulator, a metallic rod extending through said insulator, a housing of cylindrical form made of insulating material and permanently 55 secured to the end of said rod, and metallic contact devices inside of said housing connected with said rod, said contact devices comprising spring means projecting from the side walls of the housing toward the 60 center thereof and adapted yieldingly to engage a fuse device.

4. The combination of a pair of holders having sockets adapted to receive the ends 65 of a fuse device, said sockets being arranged one above and substantially axially in line

with the other, the other end of the lower socket being closed and the upper end of the upper socket being provided with a hinged cover.

5. In a fuse mounting, a socket member 70 of inverted cup-shape, adapted to receive the upper end of a cylindrical fuse device, and a metallic terminal within said socket for engaging and making contact with the upper ferrule of the fuse device, the closed 75 end of said socket comprising a hinged cover, said cover being adapted to provide a ready vent axially in line with a fuse which vents from its upper end.

6. A fuse holding clip comprising in combination, a metallic supporting rod provided with a cylindrical groove in one end, an insulating cover surrounding said rod near its grooved end, a cylindrical clip member mounted in said groove, and a cylinder 85 of insulation surrounding said clip member and extending beyond the ends thereof, said cylinder being apertured to permit said rod to contact with said clip member and fitting closely against the grooved face of 90 said cover.

7. A fuse holding clip comprising in combination, a hollow, metallic member provided with interior holding springs, an insulating cylinder surrounding said member 95 and extending beyond the ends thereof, and a cover for said cylinder movably mounted thereon.

8. A fuse holding device comprising in combination, an insulator, a copper rod 100 mounted within said insulator having a cylindrical groove in its outer end, a correspondingly grooved insulating cover piece surrounding said rod, but permitting the tip thereof to project, an insulating cylinder 105 fitted over the tip of said rod engaging the outer groove in said cover piece, a cylindrical metallic clip member mounted within said insulating cylinder contacting with the outer grooved face of said rod, screws 110 uniting said clip member with said rod, and holding springs mounted on the interior of said clip member running parallel with the axis thereof.

9. A fuse holding clip comprising in combination, a hollow, metallic clip member, springs mounted within said member running parallel to the axis thereof, an insulating cylinder surrounding said metallic member, a metallic disk closing said clip member at one end, and an insulating disk attached to said insulating cylinder on the outer side of said metallic disk.

10. The combination of a tubular socket for the end of a fuse device, said socket being substantially larger than the end of the fuse device which it has to accommodate, and stationary spring clips projecting inwardly from the sides of said socket and holding said fuse device in position and 130

making contact therewith, whereby said fuse device may be moved or swung to one side while being inserted or withdrawn.

11. The combination of a pair of stationary tubular holders and a cut-out device extending between the same, said holders having their adjacent ends open and their remote ends closed, one of said ends having an openable closure.
- 10 12. The combination of a pair of insulators 2, means for supporting the same, metallic rods 3 extending through said insulators, housings made of insulating material and secured at the ends of said rods 3, metallic sleeves inside of said housings, said metallic sleeves being secured to and in contact with the ends of said rods 3 which are extended through the walls of said housings, and metallic contact springs inside of said sleeves.
- 15 13. The combination of a pair of insulators 2, means for supporting the same, metallic rods 3 extending through said insulators, housings made of insulating material and secured at the ends of said rods 3, metallic sleeves inside of said housings, said metallic sleeves being secured to and in contact with the ends of said rods 3 which are extended through the walls of said housings,
- 20 30 and metallic contact springs inside of said sleeves, said insulators 2 being mounted one above the other and the upper housing being provided with a cover closing its upper end

and the lower housing being provided with a bottom closing its lower end.

14. In a fuse mounting, an upper inverted cup-shaped socket of relatively short length, said socket having an opening therein of a diameter substantially larger than the end of the fuse to be mounted, a plurality of 40 spring fingers converging toward the center of the opening, said fingers being connected to a suitable conductor, a lower cup-shaped socket of relatively short length having an opening therein of a diameter larger than 45 the end of the fuse to be inserted, a plurality of spring fingers converging toward the center of the opening, said fingers being connected to another conductor, said sockets being rigidly mounted axially in line with 50 their open ends spaced apart a distance less than the length of the fuse to be mounted, said upper spring fingers being sufficiently yieldable to permit the upper end of the fuse to be inserted at an angle to the axis of the 55 two sockets, and the opening in the upper socket being of sufficient depth to permit the fuse to be inserted so far that the lower end of the fuse may be brought above the top of the lower socket.

In witness whereof, I hereunto subscribe my name this 14th day of April, A. D. 1913.

NICHOLAS J. CONRAD.
